UNITED STATES PATENT OFFICE.

WALTER H. COTTON AND THOMAS D. HENDERSON, OF CHICAGO, ILLINOIS

RAILWAY-RAIL STAY.

No. 905,988.

Specification of Letters Patent.

Patented Dec. 8, 1908.

Application filed August 20, 1906. Serial No. 331,402.

To all whom it may concern:

Be it known that we, WALTER H. COTTON and THOMAS D. HENDERSON, citizens of the United States, and residents of Chicago, county of Cook, and State of Illinois, have invented certain new and useful Improvements in Railway-Rail Stays, of which the following is a specification, and which are illustrated in the accompanying drawings, forming a part thereof.

The invention relates to that class of devices which are adapted to anchor a railway rail and prevent its longitudinal creeping; its object being to secure a higher degree of efficiency than has thus far been attainable in this class of devices.

The invention consists in the device hereinafter described, and which is illustrated in the accompanying drawings, in which—

Figure 1 is a transverse section of a railway rail showing the stay in elevation; Fig. 2 is a detail plan view of the rail and of a railway tie and of the stay; Fig. 3 is a sectional view on the line 3—3 of Fig. 1, the flange of the rail being omitted; Fig. 4 is an end view of one of the members of the stay; Fig. 5 is a detail plan of a railway track with a stay applied thereto, and showing a modified form of construction; Fig. 6 is a sectional detail showing a modified form of one member of the stay.

A railway rail of ordinary form is represented at 10, and as being attached to a railway tie 11. The principal member 12 of the stay comprises a body portion 13 which extends transversely across the under face of the rail 10, a hook 14 at one end adapted to engage the edge of the foot flange of the rail, a hook 16 at the opposite end of the body portion for engaging a filler block adapted to fit against the edge of the foot flange of the rail, and a lateral tie-engaging extension 15 projecting from one end of the body portion, as shown adjacent the hook 14. The tie-engaging face of this extension 15 is rounded for the purpose of insuring a suitable bearing upon the tie, whatever angle the body portion 13 may assume.

The filler block 17 interposed between the hook 16 and the edge of the rail flange, is preferably longitudinally channeled, as shown at 18, for better engaging the rail, and its outer face is stepped, as shown at 22, 23, 24 and 25, to adapt the device for use in connection with rails of differing size, the lowest step being adjacent the tie. Each step, ex-

cept the lowest, constitutes also a shoulder against which the member 12 bears laterally when seated upon the next lower step. A similar stop shoulder 29 is provided to cooperate with the highest step 22. The filler block serves the primary purpose of providing for the convenient attachment of the double hook stay member 12 to the rail. It is obvious that it need not be provided with a plurality of steps if the device is made for use in connection with a rail of stated size.

The filler block 17 is attached to the rail by any suitable means. In the construction illustrated in Figs. 1, 2 and 3, this is accomplished by means of a threaded bolt 20, projecting through a lug 19 depending from the member 17, and having a hook 21 at its opposite end for engaging the rail flange. A nut 30, running on the thread of the bolt 20, forces the member 17 firmly against the edge of the rail flange and secures it against accidental displacement. A lock for this nut is shown as comprising a washer-plate 31, and being folded over the top of the member 17 and backwardly against one face of the nut 30.

The stay is placed adjacent the face of the tie towards which the rail tends to creep. Any movement of the rail will tend to tighten the grip of the stay upon its flange, the pressure being applied adjacent the hook 14 causing the latter to slide backwardly upon the rail, the member 12 pivoting upon the filler block 17 and hence increasing the grip of the stay upon the rail to such an extent that relative movement becomes impossible,—this grip increasing as the longitudinal strain upon the rail increases. The outer or bearing faces of the steps of the member 17 are parallel with the edge of the rail flange, and the thickness of this filler block as measured through the step in service is such that an easy though snug fit of the stay upon the rail is secured in the initial assembling. The stop shoulder of the filler block, which engages the stay member 12, prevents the latter from moving backwardly at that end, and insures the pivotal movement above referred to with its consequent increase of grip upon the rail flange, should any creeping of the rail occur.

Preferably the hook 14, which directly engages the edge of the rail flange, gives place to the form of hook shown at 32, Fig. 6, which has its recess enlarged at its inner end, as shown at 33, thereby forming a pair of jaws which engage, respectively, the upper

and lower surface of the rail flange. When this form of construction is employed, the hook recess is preferably sufficiently contracted so that the hook must be driven up 5 upon the flange, slightly spreading its jaws. This form of hook is of great strength and will firmly grip the rail without indenting it.

In the form of construction shown in Fig. 5, the hook bolt 20 gives place to a tie-rod 26 10 common to two clamping devices, one on each of the rails of the tie, the nut 30 being used as in connection with the bolt 20 and clips 27, running on the rod 26, engaging the inner edge of each rail flange and being 15 forced against the same by nuts 28 in threaded engagement with the rod. The rod 26 in this instance serves as means for preventing the rails from spreading.

We claim as our invention—

20 1. In a rail stay, in combination, a rail-engaging member having both ends upturned and having a lateral tie-engaging projection and being of greater length than the width of the rail with which it is adapted to coöperate, a filling block adapted to be interposed between the rail and one of the upturned ends of such member and having a stop for preventing movement of such member relatively as to the rail away from the tie, and 30 means for anchoring the filling block to the rail.

2. In a rail stay, in combination, a member having opposed end abutments and being adapted to cross the under side of a rail and 35 to have a tie bearing at one end only, and a shouldered filler block for insertion between the rail flange and the abutment remote from the tie-bearing and forming a pivotal bearing for the first-named member, the bearing faces 40 of the block being parallel.

3. In a rail stay, in combination, a member having opposed end abutments and being adapted to cross the under side of a rail and 45 to have a tie-bearing at one end only, a filler block for insertion between the rail flange and the abutment remote from the tie-bearing and forming a pivotal bearing for the first-named member, and having a stop shoulder for preventing lateral movement 50 thereof.

4. In a rail stay, in combination, a member having opposed end abutments and being adapted to cross the under side of a rail and 55 to have a tie-bearing at one end only, a filler block for insertion between the rail flange and the abutment remote from the tie-bearing and forming a pivotal bearing for the

first-named member and having a stop shoulder for preventing lateral movement thereof, and means for securing the filler 60 block to the rail.

5. In a rail stay, in combination, a member having opposed end abutments and being adapted to cross the under side of a rail and to have a tie-bearing at one end only, a filler 65 block for insertion between the rail flange and the abutment remote from the tie-bearing and forming a pivotal bearing for the first-named member and having a stop shoulder for preventing lateral movement 70 thereof, and a member having relatively adjustable opposed abutments for binding together the rail flange and the filler block.

6. In a rail stay, in combination, a double abutment member adapted to cross the 75 under side of a rail and to engage its flange by one abutment, a filler block for engaging the other abutment and the opposite rail-flange and having a depending apertured lug, a bolt passing through such lug and engaging the opposite rail flange, and a nut 80 running on the bolt and bearing on the outer face of the filling block.

7. In a rail stay, in combination, a bar having upturned ends and a tie-engaging 85 projection adjacent one end, of a stop-block for engaging the bar at its opposite end, and means independent of the bar for anchoring the block to the rail and being wholly exterior to the rail.

8. In a rail stay, in combination, a bar having upturned ends and a tie-engaging projection adjacent one end, of a filler block adapted to fit between the rail and the upturned end of the bar remote from the projection, and having a shoulder for engaging the side of the bar remote from the tie, the bearing faces of the block being parallel.

9. In a rail stay, in combination, a bar having upturned ends and a tie-engaging 100 projection adjacent one end, of a filler block adapted to fit between the rail and the upturned end of the bar remote from the projection and having a shoulder for engaging the side of the bar remote from the tie, the 105 bearing faces of the block being parallel, and means independent of the bar for securing the block to the rail and being wholly exterior to the rail.
